UNITED STATES PATENT OFFICE

ALFRED DILLIER, OF AESCH/BASEL, SWITZERLAND

PENCIL HAVING A SHARPENING DEVICE FOR THE LEAD

Application filed March 28, 1929, Serial No. 350,653, and in Germany April 21, 1928.

In pencils provided with a device for mechanically moving the lead outward, heretofore known, the tendency prevails to avoid the time wasting sharpening of the lead by means of a pocket knife. With this view in mind the leads were made thin. But, as the thinnest leads that can be applied with respect to their solidity, are still too thick to serve for instance as drawing pencils, it has already been proposed to depart from the thin leads which are used up relatively quickly, and to employ thicker leads which are to be sharpened by means of a sharpener, slid on the projecting portion of the lead and turnable relatively to the same, and to screw this sharpener onto the rear end of the pencil.

Further, sharpening devices are known, which are housed in the front part of the pencil casing and consist of movably arranged cutting or sharpening blades, a special device being provided to move these blades into their operative position. In order to move the lead into a position for sharpening it is necessary to retract the same from its position for writing by screw means. Other proposed constructions also require retracting of the lead by screw means in which the sharpening device is arranged in the conical part of the pencil casing proper, and in one of these constructions the sharpening of the lead only occurs during the displacement of the lead. This complicated procedure required for bringing the sharpening device and the lead in engagement with each other is a great drawback so that these known constructions could not be introduced into practice.

This drawback is eliminated in the pencil according to the invention, in that in the latter the conical sleeve together with a guide member is longitudinally displaceable relatively to the rest of the pencil casing and preferably non-detachable from the latter, in such manner, as to permit of tilting the parts towards each other into a position for sharpening. During the sharpening operation the position of the lead relatively to its tubular guide remains unchanged, as in this case the sharpening device is moved forward

to the non-displaced lead, in contradistinction to the known arrangement which required screwing the lead back into a position for sharpening.

This construction enables very quickly ascertaining whether the lead is sharpened sufficiently in that the displaceable conical sleeve together with the guide member need but be slid backwards, and if further sharpening is required it is just as quickly reset into sharpening position. The pencil according to the present invention, therefore, is a considerable progress in the art.

In the accompanying drawing several embodiments of the invention are illustrated, by way of example, in which:

Fig. 1 is a longitudinal section of a first embodiment with its parts in a position for writing;

Figs. 2, 3 and 4 are sections on the lines II—II, III—III and IV—IV in Fig. 1, respectively;

Fig. 5 shows the parts in a position which they take up when the lead is being sharpened;

Fig. 6 shows the front part of a modified embodiment of the invention;

Figs. 7 and 8 show a further embodiment of the invention in writing and sharpening position respectively;

Figs. 9, 10, 11 and 12 show details.

Fig. 13 shows a longitudinal section of a further embodiment with the parts of a pencil in their writing position;

Fig. 14 is also a longitudinal section showing the parts in sharpening position;

Fig. 15 is a section on line XV—XV in Fig. 13;

Fig. 16 is a section on line XVI—XVI in Fig. 13 and

Fig. 17 is a section on line XVII—XVII in Fig. 13.

Referring to the drawings, 1 denotes in all the embodiments of the invention the outer pencil casing, the conical front part 2 in the constructional example according to Figs. 1—5 is threadedly connected to a coupling member 3 which is adapted to be pulled out of the casing and moved into an inclined position relatively to the lead 4. For this pur-

pose a supporting member 5 secured to the casing 1 is provided with a tubular extension 6, the forward end of which is flared outwardly, and which serves for a guide for the thickened rear end 8 of the coupling member 3. The inner side of the conical sleeve is provided with an abrading surface 9 which, as shown in Fig. 3, may have sharp indentations but, alternatively, this surface may also be coated with emery. The abrading surface is preferably arranged to be exchangeable. The supporting member 5 is further provided with an interior tubular extension 10 which on its front end carries an interior screw thread 11. In the tubular extension 10 the lead holding tube 12 is guided which is flattened on two opposite sides to non-rotatably hold the lead 4 of a corresponding cross-section. The lead holding tube 12 in its front part is rotatably mounted in the tubular extension 10 of the supporting member 5 and in its rear part in an annular bearing member 13 which is connected to the casing by a cross armed support 14. To the rear end of the casing 1 a ferrule 15 is screwed in which a part 17 provided with milled surfaces 16 is rotatably mounted, and the part 17 carries a square head 18 which engages in the lead holding tube 12. In turning the parts 16 and 17 the lead holding tube 12 and the lead 4 together with it is revolved which latter thereby preferably is turned in the screw thread, whereby the forward motion of the lead is attained.

If the lead is to be sharpened, the conical front part 2 together with the coupling member 3 is pulled out of the pencil casing until the bead 8 bears on the outwardly flared part 7 of the tubular extension 6; and the sleeve 2 of the casing together with its coupling member 3 is moved into an inclined position relatively to the lead, as shown in Fig. 5, the lead remaining stationary with respect to its tubular guide 10. By turning the casing 1, i. e. the lead 4 relatively to the conical sleeve 2 which is to be revolved in the opposite direction thereto, the abrading surface trims a sharp point onto the front portion of the lead. The length of this point can be regulated at will, depending on the extent to which the lead is screwed out of the tubular guide 10. As soon as the end portion of the tubular guide 10 bears on the inner wall surface of the guide member, the sharpening operation is ceased even if the parts are further turned relatively to each other.

The same sharpening device also enables effecting of a flat point if only the cone is turned and the lead is held fast, and subsequent to the trimming of the one side of the lead the same is revolved 180° and trimming of the opposite side thereof is continued in the same manner as before.

In the constructional example according to Fig. 6 the conical sleeve 2^a provided with an

abrading surface 9 is fixed to a cylindrical coupling member 3^a which is adapted to be slid off the supporting member 5^a rigidly fixed in the casing 1. If sharpening of the lead is required the parts 2^a and 3^a are slid off the supporting member 5^a and moved to an inclined position relatively to the casing 1 on the front end of the conical part 19 of the supporting member 5^a, as indicated in dotted lines. The shoulder 20 formed by the difference in the diameters of the part 5^a and the rear portion of the part 19 serves as an abutment guide member for 3^a to bear on when the lead is being sharpened.

In the constructional example according to the Figs. 7 and 8 the conical front part or sleeve 2^b provided with an abrading surface 9 is screwed to a cylindrical sleeve 3^b and the latter is connected to a further cylindrical sleeve member 22 by means of a coil spring 21'. In this example the supporting member 5^b is again provided with a tubular extension 10^b which is formed with an external thread as at 23 and which serves as a stop for the sleeve member 22 when the latter together with the conical sleeve 2^b is slid outward in the position for sharpening. The spring 21' permits of bringing the conical sleeve 2^b in an inclined position relatively to the lead, as shown in Fig. 8, whereupon the sharpening is effected in the manner explained above. In this constructional example again the lead to be sharpened remains in writing position. Fig. 9 shows a modified form of a lead holding tube 12^b the one end portion of which is open on one side as at 24 and which when inserted into the pencil extends alongside of the magazine for the leads. This construction affords of readily exchanging the leads, for instance leads of different colours. Fig. 10 illustrates a magazine for the leads comprising a slotted lead holding tube 12^b. The magazine is provided with four chambers 21. In order to exchange the lead, the lead holding tube 12^b with its open side is moved opposite the respective chamber and while the pencil is being held horizontal the chamber is turned upwards, so that the lead can fall into the lead holding tube. To permit a precise adjustment of the ferrule relatively to the chambers, the outer surface of the pencil casing 1 and the part 16, by means of which the lead holding tube 12^b is turned, are provided with markings 25.

In order to prevent an undesired falling of a lead from the magazine into the lead holding tube 12^b which occurs for instance when the lead applied is almost used up, each lead is equipped with a metal sleeve 4' (see Fig. 11) within which it is loosely contained. The sleeve 4' together with the lead 4 can enter the lead holding tube 12^b, but it is proportioned so, that it is prevented from leaving the opened portion and protects the latter against an undesired entering of one

of the other leads contained in the magazine.

In the constructional example according to Figs. 13-17, for the purpose of effecting a flexible connection, which permits of tilting the conical sleeve relatively to the casing 1, the rear end of the coupling member 3^c is formed with a hollow spherical portion 25 and guided in a correspondingly shaped recess 26. The recess is formed between a thickened portion 27 of a sleeve 28 slidingly mounted on the tubular guide 10 for the lead supporting tube 12^c and a ring 29 fixed thereto behind the thickened portion 27. A lug shaped in the manner of a shoulder 30 is provided on the tubular guide 10 for the limitation of the longitudinal displacement of the conical sleeve 2^c, on which lug the sleeve 28 bears in its foremost position, as shown in Fig. 14. In this example, 12^c denotes the lead holding tube and 11 the interior threaded portion of the tubular guide 10 for the lead. The lead holding tube 12^c is flattened on two opposite sides to non-rotatably hold the lead 4 of a corresponding cross section. For the screw engagement of the lead, to move the same forwards, a square head 18 serves which projects in the lead holding tube and to which is screwed the plug 15 provided with milled surfaces 16.

The leads may be provided with a coating of paper or paint or some other material which facilitates cutting the threads therein.

Instead of giving the leads the cross section flattened on two opposite sides, as shown, they might have any other cross section in order to be non-rotatably held in the ferrule, for instance a square, a rectangular, a semi-circular cross-section or the like. The conical sleeve may also serve as a protecting device for the lead, in which case the lead need not be retracted at all, it always remains in writing position, whereby the sleeve is slid forward to cover the lead entirely.

I claim:

1. In a pencil of the type described, in combination, a casing having a conical front part, sharpening means arranged inside said conical front part, sharpening means arranged inside said conical front part, means to hold the lead inside the casing, coupling means between said front part and casing permitting a relative displacement of the parts longitudinally and a relative tilting of the two parts into the sharpening position, while the position of the lead remains unchanged.

2. In a pencil of the type described, in combination, a casing having a conical front part, sharpening means arranged inside said conical front part, means to hold the lead inside the casing, a coupling member rigidly fixed to said conical front part and guided and longitudinally displaceable in

said casing, and means connecting said coupling member to other parts fixed to said casing, said connecting means permitting a tilting of said conical front part into the sharpening position against the lead while the position of the lead after withdrawal of the coupling member from the casing remains unchanged.

3. In a pencil of the type described, in combination, a casing having a conical front part, sharpening means arranged inside said conical front part, means to hold the lead inside the casing, a coupling member rigidly fixed to said conical front part and guided and longitudinally displaceable in said casing, a sleeve in said casing, and a connection between said sleeve and said coupling member and slideable with the latter, a shoulder on the lead holding means against which said sleeve abuts to limit the withdrawal of the coupling member while permitting a tilting of said conical front part into the sharpening position against the lead while the position of the lead remains unchanged.

4. In a pencil of the type described, in combination, a casing having a conical front part, sharpening means arranged inside said conical front part, means to hold the lead inside the casing, a coupling member rigidly fixed to said conical front part and guided and longitudinally displaceable in said casing, a tubular guide member in rigid connection with the casing, a further sleeve slideable on said tubular guide member, and a flexible connection between said coupling member and said further sleeve to permit a tilting of said conical front part against the lead into the sharpening position while the coupling member is withdrawn from the casing and the position of the lead remains unchanged.

5. In a pencil of the type described, in combination, a casing having a conical front part, sharpening means arranged inside said conical front part, means to hold the lead inside the casing, a coupling member rigidly fixed to said conical front part and guided and longitudinally displaceable in said casing, a tubular guide member in rigid connection with the casing, a further sleeve slideable on said tubular guide member, and a flexible connection between said coupling member and said further sleeve comprising a hollow spherical portion on the rear end of said coupling member and a correspondingly shaped recess provided on said further sleeve with which that portion engages to permit a tilting of said conical front part against the lead into the sharpening position while the coupling member is withdrawn from the casing and the position of the lead remains unchanged.

6. In a pencil of the type described, in combination, a casing having a conical front part,

sharpening means arranged inside said conical front part, means to hold the lead inside the casing, a coupling member rigidly fixed to said conical front part and guided and longitudinally displaceable in said casing, a 5 tubular guide member in rigid connection with the casing, a further sleeve slidable on said tubular guide member, and a flexible connection between said guide member and 10 said further sleeve comprising a hollow spherical portion on the rear end of said coupling member and a corresponding shaped recess provided on said further sleeve with which that portion engages to permit a tilting of said conical front part against the lead 15 into the sharpening position while the coupling member is withdrawn from the casing and the position of the lead remains unchanged, and means to limit the longitudinal 20 displacement of said conical sleeve relatively to said casing.

7. In a pencil of the type described in combination, a casing having a conical front part, sharpening means arranged in the 25 front part, lead supporting means in the casing, coupling means between the front part and casing capable of being slid longitudinally and universally tilted to bring said sharpening means into sharpening engagement with the lead, and means to limit the longitudinal movement of said front part and coupling means.

8. In a pencil of the type described in combination, a casing, a lead supporting tube 35 mounted therein, a longitudinally movable sleeve slidably supported on the lead supporting tube, a front part, abrading means therein, coupling means between said front part and said sleeve and permitting universal 40 movement of said front part when longitudinally withdrawn with respect to the casing, and means to limit the movement of the coupling means connected to said front part.

9. In a pencil of the type described, in 45 combination, a casing having a conical front part, sharpening means arranged inside said conical front part, means to hold the lead inside the casing, a sleeve guided and longitudinally displaceable relatively to said casing, and a coil spring interconnecting said 50 conical front part and said sleeve and permitting a tilting of said conical front part against the casing into the sharpening position in which the position of the lead remains unchanged.

10. In a pencil of the type described, in 60 combination, a casing having a conical front part, sharpening means arranged inside said conical front part, means to hold the lead inside the casing, a guide member rigidly fixed to said conical front part and guided and longitudinally displaceable in said casing, a sleeve rigidly fixed in said casing, and a flexible connection between said sleeve and 65 said guide member and comprising a beaded

portion on the guide member and an outwardly flared edge on the sleeve and permitting a tilting of said conical front part against the casing into the sharpening position in which the position of the lead remains unchanged. 70

In testimony whereof I have signed my name to this specification.

ALFRED DILLIER.
